UNITED STATES PATENT OFFICE.

JAMES F. McELROY, OF ALBANY, NEW YORK, ASSIGNOR TO THE CONSOLIDATED CAR-HEATING COMPANY, OF SAME PLACE.

DESIGN FOR AN ELECTRIC-HEATER CASE.

SPECIFICATION forming part of Design No. 24,459, dated July 2, 1895.

Application filed March 7, 1895. Serial No. 540,897. Term of patent 14 years.

To all whom it may concern:

Be it known that I, JAMES F. McELROY, a citizen of the United States, residing in the city and county of Albany, State of New York, have invented and produced a new and original Design for Electric-Heater Cases, of which the following is a specification, reference being had to the accompanying drawings, forming a part thereof.

In Figure 1 my invention is shown in perspective. Fig. 2 is a cross-section. Fig. 3 is a section along the line 1 1 on Fig. 2.

My electric-heater case is of oblong shape, concavo-convex at the upper and lower edges and at the ends, its central flattened surface being usually provided with raised panel decoration, perforations extending through the top and bottom.

The leading feature of my design consists in an electric-heater case of the shape shown, ^{2c} having its front central portion a flat surface, the sides and ends being curved backward from the front, forming concavo-convex borders, with a series of openings extending through the case along the upper and lower ²⁵ concavo-convex surfaces.

What I claim as my invention, and desire to secure by Letters Patent, is—

The design for an electric heater case as herein shown and described.

JAMES F. McELROY.
